AUTOMATIC BLOCK SIGNAL SYSTEM FOR
RAILROADS

Daniel J. Murphy, Chili, N. Y., assignor to General Railway Signal Company, Rochester, N. Y.

Application November 14, 1936, Serial No. 110,860

5 Claims. (Cl. 246—50)

This invention relates to automatic block signal systems and has particular reference to a four indication signal system employing a minimum number of line wires.

5 In automatic block signal systems it is expedient to employ a minimum number of line circuits between signal locations both because of the cost of line wire as well as the increased cost of maintenance of a larger number of wires over 10 the considerable distances between adjacent signal locations.

With this and other considerations in view it is proposed in accordance with this invention to provide a four indication automatic block signal system operable over a two-wire line circuit. In order to accomplish this it is proposed to employ signals having two indicators and control one of 15 these indicators by direct current applied to the line circuit and control the other indicator by 20 alternating current superimposed on the same line circuit.

Another purpose of this invention is to provide means for operating the signal indicators in the event of a failure of the normal alternating current supply.

25 Other purposes, objects and characteristic features of this invention will be in part obvious from the accompanying drawings and in part pointed out as the description of the invention progresses.

30 In describing the invention reference will be made to the accompanying drawings which when placed end to end with Fig. 1 to the right of Fig. 2 and with corresponding numbered lines in alignment, constitutes a drawing which shows the invention applied to a stretch of single track which has been divided by the usual insulated joints into four sections or blocks 1, 2, 3 and 4 with an arrow indicating the direction of traffic over the trackway. These drawings illustrate 35 only a part of a complete signal system and some of the relays and circuits have been omitted to simplify the illustration.

For the purpose of further simplifying the illustration and facilitating in the explanation thereof, various parts and circuits constituting the embodiment of the invention have been shown diagrammatically and certain conventional illustrations have been employed. The drawings have 45 been made with the idea of making clear the purposes and principles of the invention together with the mode of operation rather than with the idea of construction and arrangement of parts that would probably be employed in practice.

50 Symbols (+) and (—) are employed to indicate the positive and negative terminals respectively of suitable batteries or other sources of direct current and those terminals with which these symbols are used are presumed to have 55 current flowing from the positive terminal design-

nated (+) to the negative terminal designated (—). Where alternating current is used the symbols (±) and (±) are employed to designate the polarities at the respective terminals of a suitable source of alternating current.

5 Symbols employed with any one circuit are considered to designate a single source of energy in the embodiment of the present invention but as many sources may be provided as found necessary or expedient in practicing the invention.

Apparatus

Referring to Fig. 1 of the accompanying drawings the trackway has been shown divided into track sections 1, 2 and 3 by the usual insulated joints, sections 1 and 2 and the adjacent end of section 3 being shown. At the entrance ends of sections 1 and 2, signals S¹ and S², conveniently referred to as two arm signals, are shown, each arm being a search light type signal such as disclosed in Patent No. 1,835,150, issued December 8, 1931, to O. S. Field. Since the apparatus associated with these signals as well as the apparatus associated with signals S³ and S⁴ in Fig. 2, are the same at each signal location it will suffice 15 to describe the apparatus at one signal location, like parts at other signal locations being designated by like reference characters having distinctive exponents.

20 Referring to the signal apparatus located at the entrance to section 1 or at signal S¹, the top or upper arm of signal S¹ has been designated by the reference character UA¹ and has a movable element or rotor 6¹ which is controlled in accordance with the polarity of the direct current applied to an operating winding 7¹. Rotor 6¹ has been shown carrying a spectacle containing a green lens G, a red lens R, and a yellow lens Y, the rotor being biased to position the red lens R at the focal point of the light beam from a lamp L when the operating winding 7¹ of signal 25 UA¹ is deenergized.

30 The search light type signal UA¹ has movable contacts 8¹ and 9¹, contact 8¹ being in engagement with the stationary contact 10¹ when the signal displays a green indication and is in engagement with the stationary contact 11¹ when the signal displays a yellow or red indication whereas contact 9¹ is in engagement with the stationary contact 12¹ when the signal displays a 35 yellow indication and is in engagement with contact 13¹ when the signal displays a red or green indication.

40 Slow release relays GP¹ and YP¹ are provided to repeat the yellow and green positions respectively of the upper arm signal UA¹ and are energized through obvious circuits in accordance with the position of the signal contacts 8¹ and 9¹. These relays are made slow release to take care 45 of the time interval required for the signal mech- 50 55 60

anism to move from the yellow through the red to the green position or vice versa, to prevent a momentary change of indication at the signals to the rear of signal S¹.

5 At each signal location there is a direct current neutral line relay which at signal S¹ is designated by the reference character LR¹. This relay when energized receives direct current from the output side of a double wave rectifier RECT¹ which 10 has its input terminals connected to the secondary of a transformer TR¹.

The lower arm of signal S¹ is a search light type signal LA¹ which is similar to the upper arm signal UA¹ except that its operating coil 14¹ is controlled by a circuit polarized so as to operate the signal only to the green and red positions. To guard against the possibility of a movement of the signal to the yellow position the yellow lens in the spectacle has been replaced by a red 20 lens.

20 The lamp L of upper arm signal UA¹ is normally energized by alternating current through front contacts 15¹ and 16¹ of a power off relay PO¹ which relay will become deenergized and open 25 its front contacts when the local alternating current power supply fails and direct current will then be supplied to the lamp L through the back points of contacts 15¹ and 16¹. Lamp L of signal LA¹ is energized in a similar manner through contacts 17¹ and 18¹ of the same power off relay. Alternating current is also supplied 30 through front contacts 19¹ and 20¹ of relay PO¹ to the primary of transformer TRA¹ the secondary of which is connected in series with the line circuit extending between signal S¹ and signal S².

35 A vibrator inverter VI¹ of a type commonly used in automobile radio circuits is provided for applying interrupted direct current to the secondary of transformer TRA¹ in the event of an alternating current power failure.

Operation

Having thus described in general the location and arrangement of the various parts comprising 45 the present invention, the operation of the apparatus at each location will now be described in detail, the signals, relays and circuits in the accompanying drawings being shown in the positions they would assume with a vehicle V occupying section 1 of the trackway.

50 Referring to Fig. 1, due to the presence of vehicle V in section 1, track relay T¹ will be deenergized and its front contacts 38¹ and 21¹ will be open thereby disconnecting at this location the line wires 22¹ and 23¹ that extend to the next location in advance. These line wires are employed to carry direct current energy for energizing the operation winding 7¹ of upper arm signal UA¹ and also to carry alternating current for 55 energizing the primary of transformer TR¹. With track relay T¹ deenergized, rotor 6¹ of signal UA¹ will assume its neutral biased position and the red indication will be displayed on the upper arm of signal S¹. With energy removed from the 60 primary of transformer TR¹, line relay LR¹ will be deenergized and the energizing circuit for operating winding 14¹ of signal LA¹ is broken at contact 26¹ which results in signal LA¹ assuming its neutral position causing the red indication 65 to be displayed on the lower arm of signal S¹. Thus with a vehicle occupying section 1, signal S¹ will display a red over red indication which means that the block in advance is occupied.

70 At section 2 track relay T² will be energized and its front contacts 38² and 21² will close a

circuit for energizing the operating winding 7² of signal UA² with current of a polarity that will hereinafter be referred to as current of normal polarity. Signal UA² will be positioned to display the yellow indication as shown in the drawings and contact 9² will make up with stationary contact 12² thereby energizing the repeater relay YP² through an obvious circuit. The circuit for operating UA² may be traced from (+) battery, back contact 27¹ of relay LR¹, secondary winding 10 of transformer TRA¹, line wire 23² front contact 21² of relay T², winding 7² of signal UA², front contact 38² of relay T², line wire 22² back contact 28¹ of relay LR¹, to (-) battery.

15 Relay LR² is normally energized by rectified alternating current from signal location S¹ through a circuit that includes transformer TRA¹ at signal location S¹ and transformer TR² at signal location S². As previously described the secondary of transformer TR² supplies energy to the input side of rectifier RECT² for energizing relay LR² and the primary of transformer TR² is normally energized through a circuit that may be traced from the left side of the secondary coil 20 of transformer TRA¹, line wire 23², front contact 21² of relay T², wire 29², either front contact 34² of relay YP² or front contact 32² of relay GP², primary of transformer TR², wire 30², front contact 38² of relay T², line wire 22², back contact 29¹ of relay LR¹, through the local battery 25 at signal location S¹, back contact 27¹ of relay LR¹ to the other side of the secondary coil of transformer TRA¹. Transformer TRA¹ is energized through a circuit that may be traced from (±), front contact 19¹ of relay PO¹, the right portion of the primary coil of transformer TRA¹ 30 intermediate tap of the same transformer, either front contact 24¹ of relay GP¹ or front contact 25¹ of relay YP¹, front contact 20¹ of relay PO¹, to (±) of the source of alternating current.

35 As previously noted with the vehicle V in section 1, the repeater relays GP¹ and YP¹ are deenergized and under these conditions the circuit that includes the primary of transformer TRA¹ is open and it is therefore obvious that no energy 40 will be supplied to the primary of transformer TR² for energizing the line relay LR². The operating winding 14² of lower arm signal LA² is normally energized by direct current through a circuit that includes the front contact 26² of relay LR², back contact 33² of relay GP² and front contact 34² of relay YP² but with line relay LR² deenergized energy is removed from the operating winding 14² and the lower arm signal LA² is positioned as shown in the drawings to display 45 a red indication. Signal S² at the entrance to section 2 of the trackway will therefore display 50 a yellow over red indication which denotes occupancy of the second block in advance.

55 Referring now to the operation of the apparatus at signal location S³, by reason of the fact that relay LR³ at signal location S² is deenergized, the operating winding 7³ of signal UA³ is energized by direct current of normal polarity, through a circuit similar to the circuit previously 60 traced for signal UA² at signal location S² which actuates the signal to its yellow position and energizes repeater relay YP³. However, at signal location S³ relay LR³ will be energized as relay 65 GY² at location S² is energized and its front contact 25² completes a circuit for energizing transformer TRA² which in turn energized relay LR³ through a circuit similar to the circuit traced 70 for controlling relay LR².

75 With relay LR³ energized contact 26³ is picked 75

up thereby closing a circuit for energizing the operating winding 14³ of signal LA³ which will now display a green indication. This circuit may be traced from (+) battery, front contact 26³ of relay LR³, back contact 33³ of relay GP³, front contact 34³ of relay YP³, operating winding 14³ of signal LA³, to (-) battery. Under the above conditions signal S³ at the entrance to section 3 will display a yellow over green indication which denotes occupancy of the third block in advance.

Referring to the operation of signal S⁴ at the entrance of section 4 of the trackway, with line relay LR³ at signal location S³ energized, current 15 of reverse polarity will now be applied to a circuit which includes front contacts 27³ and 28³ of relay LR³ to the operating winding 7⁴ of signal UA⁴ which will actuate the signal to its green position as shown in Fig. 2 of the drawings. This 20 will operate contact 8⁴ to its right hand position and an obvious circuit for energizing the repeater relay GP⁴ will be closed at contact 10⁴.

Relay LR⁴ at this location will be picked up through an energizing circuit similar to the circuit described for energizing relay LR³ at signal location S³ with the exception that the circuit for energizing transformer TR⁴ is closed through front contact 32⁴ of relay GP⁴ instead of front contact 31³ of relay YP³ as was the case at signal location S³. With relay GP⁴ picked up and relay YP⁴ deenergized the circuit for the operating winding 14⁴ of signal LA⁴ is opened at contacts 33⁴ and 34⁴ respectively and the signal LA⁴ will be energized to display the red indication. 35 Thus it will be noted that signal S⁴ at the entrance end of section 4 will display a green over red indication which means that the three blocks in advance are unoccupied.

The signals to the rear of signal S⁴ will display the green over red indication, the top arm signal UA at each signal location being operated to its green position due to the LR relay in advance being picked up and with the top arm signal energized to the green position the GP 40 and YP relays are energized and deenergized respectively thereby breaking the energizing circuit of the lower arm signal and causing it to display the red indication all in a manner previously described.

Having described the normal operation of a four-wire automatic block signal system controlled over two line wires and employing alternating current and direct current for control purposes, the arrangement provided for operating the system in the event of a failure of the alternating current power supply will now be taken up in detail.

Let us assume that a failure of the alternating current supply occurs at signal location S², 60 it being understood that the apparatus at all the other signal locations will function in a similar manner if there is a failure of the transmission line.

An alternating current power failure at signal location S² will deenergize relay PO² and direct current will be supplied to lamps L of signals UA² and LA² as previously described, and the closure of the back contacts 19² and 20² of relay PO² will introduce the vibrating inverter VI² into the primary circuit of transformer TRA². With contacts 19² and 20² closed, a coil C² of vibrating inverter VI² is energized through a circuit that may be traced from (+) battery, back contact 28² of relay PO², front contact 25² of relay YP², intermediate tap of transformer TRA², 75

the right portion of the primary coil of transformer TRA², back contact 19² of relay PO², coil C² of vibrating inverter VI² to (-) battery. The energization of coil C² will operate vibrating armature 35², which is preferably of the vibrating reed type, to its upper position and close contact 36² which when closed shunts coil C² thereby releasing armature 35². Armature 35² being biased slightly downward as shown in the drawings will, when released, move downward a sufficient distance to engage its associated lower contact 37².

When armature 35² is in its upper position and engaged with contact 36² the circuit just described energizes the right portion of transformer TRA² and when armature 35² is in its extreme downward position a circuit for energizing the other half of transformer TRA², with current flowing in the opposite direction, is completed which may be traced from (+) battery, back contact 20² of relay PO², front contact 25² of relay YP², the left portion of the primary coil of transformer TRA², lower contact 37² and armature 35² of vibrating inverter VI² to (-) battery.

It will be noted that when the shunt is removed from coil C² and armature 35² releases, the coil C² will again become energized and attract armature 35² which will again release and make up with lower contact 37² when coil C² is shunted. This repeated energization and shunting of coil C² causes armature 35² to vibrate rapidly between its upper and lower contacts thereby applying direct current of first one polarity and then the other to the primary of transformer TRA² and inducing in the secondary of transformer TRA² an alternating current of a frequency corresponding to the vibrating rate of armature 35².

It may be pointed out here that upper arm signals UA are inherently direct current devices, 40 and the alternating current superimposed on their respective control circuits will not effect their operation. However, it is intended to be within the scope of the invention to employ choke means in the direct current circuit to 45 block out the alternating current if a less inherently direct current device is employed. It will also be noted that direct current will not effect the operation of lower arm signals LA as transformers TR in the alternating current circuits 50 block out the direct current at that point.

The particular construction and arrangement of circuits shown and described represents only one particular embodiment of the present invention and is merely typical or illustrative of 55 the principles, functions, and mode of operation of the invention, and it should be understood that various adaptations, modifications, and additions may be made in this particular arrangement, without departing from the scope 60 of the invention.

What I claim is:

1. In a signal system for railroads, in combination; a stretch of track divided into track sections; a signal located at the entrance of each track section having a first and a second indicator; an operating mechanism for each first and second indicator; one line circuit only for interconnecting adjacent signals; means for controlling said signals by applying direct and alternating current to said one line circuit in accordance with traffic conditions ahead, the first indicator of each signal being distinctively controlled by relay means at the signal location next in advance, which relay means is con- 75

- trolled by the condition of the first indicator of the associated signal and the first indicator of the signal next in advance thereof, and the second indicator of each signal of which is distinctly controlled by the condition of the first indicator of the associated signal and of the first indicator of the signal next in advance.
2. In a signal system for railroads; the combination with a stretch of track divided into track sections each having a track relay; a signal comprising two signal mechanisms located at the entrance end of each section, each signal mechanism including an electro-magnetically operated spectacle and contacts; a control circuit for one of said mechanisms including line wires extending to the signal in advance and including contacts controlled by the track relay of the section in advance and contacts controlled by the signal in advance and energized by direct current, and a control circuit for the other of said mechanism energized by alternating current flowing over the same line wires and including contacts controlled by the signal in advance and contacts controlled by said one mechanism, whereby said other mechanism depends for its operation on the position assumed by said one mechanism and also on the position assumed by the mechanism in advance.
3. In a signal system for railroads, the combination with a stretch of track divided into track sections each having a track circuit including a normally energized track relay, a signal at the entrance end of each section including electrically operated mechanism for operating a spectacle and contacts, said electrically operated mechanism being operated to a clear position if current of one polarity is applied thereto through a line circuit including front contacts of the track relay of the section in advance and controlled by the signal in advance and being operated to the caution position if current of the opposite polarity is applied thereto, two slow dropping relays associated with each signal neither of which is energized if the mechanism of said signal assumes the stop position, one relay of which has an energizing circuit including a contact of said mechanism closed only when said mechanism assumes a clear position and the other relay of which is provided with an energizing circuit including a contact of said mechanism closed only when said mechanism assumes a caution position, and means for applying current of one polarity to said line circuit when either of the slow dropping relays of the signal in advance is in its energized condition and for applying current of reverse polarity to said line circuit when both of the slow dropping relays associated with the signal in advance are in their retracted condition, whereby said circuit is not momentarily pole changed if the signal in advance changes from clear to caution or from caution to clear but is pole changed if such signal in advance is moved to the stop position.
4. In a signal system for railroads, the combination with a stretch of track divided into track sections each having a track circuit including a track relay, a signal at the entrance end of each section including electrically operated mechanism for operating a spectacle and contacts, said electrically operated mechanism being operated to a clear position if current of one polarity is applied thereto and being operated to the caution position if current of the opposite polarity is applied thereto, a line circuit

circuit including front contacts of the track relay of the section in advance for controlling said mechanism, two slow dropping relays associated with each signal neither of which is energized if the mechanism of said signal assumes the stop position, one relay of which has an energizing circuit including a contact of said mechanism closed when said mechanism assumes a clear position and the other relay of which is provided with an energizing circuit including a contact of said mechanism closed when said mechanism assumes a caution position, means for applying current of one polarity to said line circuit when either of the slow dropping relays of the signal in advance is in its energized condition and for applying current of reverse polarity to said line circuit when both of the slow dropping relays associated with the signal in advance are in their retracted condition, whereby said circuit is not momentarily pole changed if the signal in advance changes from clear to caution or from caution to clear but is pole changed if such signal in advance is moved to the stop position, and an auxiliary signal controlled by said slow dropping relays.

5. In a signal system for railroads, the combination with a stretch of track divided by insulating joints into track sections each including a track circuit having a track relay, two signals at the entrance end of each block one of which includes an operating mechanism capable of assuming a clear, caution and a stop position and operating a color screen spectacle and operating contacts, two slow dropping relays associated with said operating mechanism, one of said slow dropping relays having an energizing circuit including one of said contacts closed only when said mechanism assumes the clear position and the other of said slow dropping relays having an energizing circuit including another of said contacts closed only when said mechanism assumes the caution position, a line circuit extending to the next signal location in advance and including a front contact of the track relay of the track section in advance and connected to said signal mechanism and operating said signal mechanism to the clear position when energized by direct current of one polarity and operating it to the caution position when energized by direct current of reverse polarity, a transformer connected in multiple with the energizing winding of said mechanism through a circuit including in multiple front contacts of the slow dropping relays associated with said mechanism, a signal relay for controlling a second signal at the same location energized from the secondary winding of the transformer at that location, and means at the signal location in advance for applying direct current of one polarity and alternating current to said line circuit when the signal relay and one of the slow dropping relays at such signal location in advance are in their energized condition and for applying only direct current of the opposite polarity to said line circuit when both slow dropping relays and the signal relay at said location in advance are in their deenergized condition, whereby said second signal at any location cannot have its control circuit energized unless its associated signal assumes either the clear or the caution position and whereby a change from clear to caution or from caution to clear of a signal mechanism will not affect the signal mechanism in the rear.
